Continuation of application Serial No. 761,866,
July 18, 1947. This application March 31, 1949,
Serial No. 84,527

19 Claims. (Cl. 103—38)

1

This invention relates to pumps and especially to variable volume positive displacement pumps of the type in which working pistons also perform the function of valving the fluid displaced by other pistons. This application is a continuation of my application Serial Number 761,866, filed July 18, 1947.

An object of this invention is to provide a pump having an improved construction and arrangement for accomplishing the required results with efficiency and relative economy.

A further object is to provide a wobble disk pump constructed and arranged to substantially eliminate scoring of the cylinder walls resulting from side thrust on the pistons.

A still further object is to provide a wobble disk pump of the opposed cylinder type having an improved mechanism for reciprocating the pistons and for varying the piston stroke.

A still further object is to provide a positive displacement hydraulic pump with an improved mechanism for valving the cylinders.

Other objects will appear from the following description of an illustrative embodiment of the invention taken in connection with the accompanying drawings in which:

Fig. 1 is a longitudinal sectional view through a pump constructed in accordance with one embodiment of this invention;

Fig. 2 is a transverse sectional view on the line 2—2 of Fig. 1;

Fig. 3 is a section on the line 3—3 of Fig. 1;

Fig. 4 is a diagrammatic layout of the cylinder block and pistons, showing the method of and arrangement for valving the cylinders;

Fig. 5 is a perspective view, with parts broken away, to show the manner of valving the pump cylinders;

Fig. 6 is an exploded view of certain wobble disk details;

Fig. 7 is a longitudinal sectional view similar to Fig. 1, showing a pump of modified construction taken on line 7—7 of Fig. 8;

Fig. 8 is a transverse cross-sectional view of the construction of Fig. 7 taken on the line 8—8 of Fig. 7;

Fig. 9 is a perspective view with parts broken away showing the construction of Fig. 7; and

Fig. 10 is a diagrammatic layout of the cylinder block and pistons showing the relative positions of the various pistons and their motion.

In general, the invention comprises a relatively rotatable shaft and cylinder block in which axially extending cylinders are arranged in inter-spersed pairs. The pistons in each pair of cyl-

inders have rods or stems extending outwardly in opposite directions, and separate, angularly adjustable, wobble disks are mounted for rotation by the shaft for reciprocating the separate groups of pistons. Each cylinder of each pair has a pressure chamber portion and a valve chamber portion. The pressure chamber of each cylinder in each pair communicates with pump inlet and delivery manifolds through the valve chamber portion of the other cylinder in the pair, and each piston has a body portion formed to provide a slide valve for controlling the valving of the adjacent cylinder. For proper valving, the piston is one of each pair of cylinders is displaced from the other of its pair by a 90° phase difference, and this is accomplished by a suitable angular mounting of the separate wobble disks relative to each other.

The mechanism by which the wobble disks reciprocate the pistons is such that the pistons are substantially free of side thrust on the cylinder walls so that scoring from this cause is substantially eliminated. Volume delivery of the pump is varied by simultaneously varying the strokes of all pistons, and this is accomplished by a simple mechanism for simultaneously adjusting the angles of the separate wobble disks relative to the axis of the supporting shaft.

In the drawings, the invention is illustrated as comprising a stationary cylinder block 11 and rotatable pump shaft 12. The block includes a plurality of pairs of cylinder bores 13, 14. Pistons 15 and 16 are reciprocably mounted in each pair of cylinders 13, 14, respectively, and have stems 17 and 18 extending outwardly in opposite directions.

An annular housing 21 surrounds the cylinder block 11 and is provided with a pump delivery manifold 22 communicating with an annular port 23, common to all pump cylinders 13 and 14. The annular housing also has a pump inlet manifold 24 communicating through an annular port 25 in the cylinder block with the valve chamber portions 25 of the cylinders 13 of each pair, cylinder heads 26 being provided in each cylinder 14 for closing off such cylinders from the port 25 and providing pressure chambers 27 therein. A second pump inlet manifold 28 is provided in the opposite side of the housing 21 and communicates with the valve chambers 29 of cylinders 14 of each pair through an annular port 31 in the cylinder block. The port 31 is closed off from the other cylinders 13 of each pair by cylinder heads 32 which provide pressure chambers 33 in the cylinders 13.

With reference to each pair of cylinders (see also Figs 4 and 5), the piston 15 in cylinder 13 alternately connects the inlet manifold 24 and the delivery manifold 22 with the pressure chamber 21 of the adjacent cylinder 14 through a valve passage 34 connecting such pressure chamber 21 with the valve chamber portion 25' of the adjacent cylinder 13. Similarly, the piston 16 in the cylinder 14 alternately connects the pressure chamber 33 in the adjacent cylinder 13 with the inlet manifold 28 and the exhaust manifold 22 through a valve passage 34' connecting the valve chamber portion of cylinder 14 with the pressure chamber 33 of the adjacent cylinder 13.

The piston rods 17 on the group of pistons 15 extend outwardly in one direction, toward the left in Fig. 1, while the rods 18 on the group of pistons 16 extend outwardly in the opposite direction.

A wobble disk 35 is arranged to reciprocate the group of pistons 15 while a second wobble disk 36 is arranged to reciprocate the other group of pistons 16. Each wobble disk is supported on the pump shaft 12 for rotation therewith and is angularly adjustable thereon to vary the piston stroke of the pump. Each wobble disk comprises a counter-balanced hub 37 pivotally supported on the pump shaft by a pin 38 extending through the shaft and hub. An annular wobble plate 39 is clamped against a positioning shoulder 40 on each hub 37 by a nut 41 and is arranged to reciprocate the associated group of pistons through slideable crossheads of such construction as to substantially prevent the transmission of side thrust to the pistons from the wobble disks. As illustrated, this mechanism includes wear members 42, 43 of partial ball shape having their flat faces frictionally engaging opposite sides of the annular wobble plate 39. These wear members are so formed that their centers of curvature lie in the central plane of the wobble plate 39. The wear members are seated in cup members 44, 45, respectively, which are in turn positioned in a slotted sleeve 46 slidably mounted in a supporting cylinder 47 formed in a wobble plate housing 48 which is secured to one side of the cylinder block 11 and manifold member 21 so as to enclose the associated wobble disk and piston rods. The wobble plate 41 extends inwardly between the wear members 42 and 43 through the slotted wall of the sleeve 46, the latter being in line with the associated piston rod. Each cup 44 and 45 has a flange 49 engaging the sleeve on one side of the slot and a spring plate 50 assists in positioning and holding the cup 44 in the sleeve.

The associated piston 17 is loosely connected to the sleeve 46 to permit a slight radial movement therebetween. This is illustrated as formed by a snap-ring 51 mounted in a groove in the adjacent piston rod and positioned so as to bear against an inner flange 52 in the sleeve 46 on the outward stroke of the piston when the sleeve 46 is drawing the associated piston outwardly. On the inward stroke of the piston the cup member 45 bears against the end of the piston rod. A slight amount of radial play is provided between the piston 17 and the interior flange 52 and the ring 51 is so dimensioned as to permit such radial play. As a result, it will be apparent that substantially no lateral thrust is applied to the piston. Such lateral thrust as results from operation of the wobble disk will be substantially entirely absorbed by the reciprocating sleeve 46 and the supporting housing 48, the engaging surfaces of which can be easily lubricated. The prevention

of lateral pressure of the pistons on the cylinder walls renders the pump particularly adapted for the pumping of any fluid which interferes with cylinder wall lubrication.

5 The housings 48 on each side of the cylinder block rotatably support the pump shaft through ball bearings 54 which are secured to the housings and the pump shaft in any suitable manner.

10 As best shown in Fig. 6 each wobble disk is counterweighted to balance both the wobble disk itself and also the rotating moment produced by reciprocation of the pistons. Each hub 37 has spaced counterweights 55 formed as part of the hub portion. A separable counterweight member 56 is also mounted on the opposite face of the hub by suitable bolts 57. Both counterweights are slotted to permit angular adjustment of the wobble disk on the pump shaft.

15 The volume delivery of the pump is varied by 20 piston stroke adjustment which is in turn accomplished by controlling the angles of the wobble disks relative to the shaft axis. In the present invention a disk-adjusting sleeve 61 is slidably supported on the pump shaft 12 and connected to each wobble disk hub 37 by a pin 62 mounted in a pin block 63 positioned in a groove 64 of the sleeve 61, and engaging openings in the associated hub portion 37 on one side of the pump shaft. The sleeve 61 can be moved longitudinally 25 of the pump shaft by any suitable mechanism such, for example, as a crosshead 66, mounted within the hollow pump shaft and connected to the sleeve 61 by a pin 67 extending through diametrically opposite slots 68 in the shaft. A rod 30 69 or the like extends outwardly from the crosshead 66 to be actuated in any desired manner. The opposite end of the pump shaft is shown with splines 71 for connection to any suitable source 35 of power.

40 As heretofore pointed out, in order to provide for proper valving of the cylinders by the associated pistons, it is necessary that the piston in one cylinder of each pair be displaced from the other piston of that pair by a phase difference of 45 substantially 90°. In other words, in the present invention, one group of pistons, for example those in cylinders 13, lead the other group of pistons, those in cylinders 14, by a phase difference of 90°. This is accomplished by mounting the wobble disk actuating the first group of pistons in such a way that the supporting pin 38 extends through the pump shaft at the required angle to the pin 38 supporting the other disk. In the illustrated embodiment which shows an 18 cylinder pump, it will be apparent that the cylinders of each pair are 20° apart from each other, therefore the wobble disk actuating the pistons in the cylinders 13, for example, is supported on a pin positioned at an angle of 70° to the pin 50 supporting the other wobble disk, as shown in 55 Fig. 1.

60 Rotation of the pump shaft by a suitable prime mover operates the wobble disks to reciprocate the various pistons, the stroke depending upon 65 the adjustment of the sleeve 61 controlling the disk angle. Inward movement of a piston operating crosshead by a wobble disk causes the associated cup member 45 to engage the adjacent end of the piston rod 17 to move it inwardly 70 without transmitting lateral thrust to the associated piston and cylinder wall. Reverse movement of the crosshead moves the cup member 45 out of contact with the piston rod and causes the flange 52 of the slideable sleeve 46 to engage 75 the ring 51 on the piston rod and draw the pis-

ton in the opposite direction. The valving of each cylinder is controlled and operated by the reciprocation of the combined piston-valve in the associated cylinder. The arrangement is such as to provide the necessary 90° lead of one piston by the other. Also, the associated cylinders are closely adjacent to each other, so that the proper valve timing is obtained without the necessity of elongated valve passages between the associated cylinders. The angle-controlling sleeve 61 is easily adjusted by the rod 69 to vary the pump stroke.

The operation and valving is best illustrated in the diagram of Fig. 4. In this diagram each point 72 indicates the center of the ball formed by the wear members 42, 43, at which point the reciprocating force of the wobble disk is applied to the associated piston in line with the axis thereof.

The directions of movement of the various pistons are indicated by the arrows appearing thereon; similarly, curved arrows indicate the flow of the working fluid at the time indicated.

It will be noted that four pistons of the group designated 16 are on their upward (intake) stroke. It will also be noted that at this time, the fluid is so valved by the adjacent piston of the other group of pistons (15) that fluid is drawn from the lower manifold 24.

By referring to those pistons 16 which are on their downward stroke (delivery) it will be noted that the fluid displaced thereby is discharged into the manifold 22. It will be noted that four of the pistons 15 are on their downward (intake) stroke and that they draw fluid from the same manifold 22 to which the pistons 16 deliver their fluid.

It will also be noted that those pistons 15 which are on their upward (delivery) stroke discharge their fluid into the manifold 28. From the above it will be seen that the arrangement is such that a two stage pump is provided. The pistons 16 serve to raise the pressure of the fluid from, say, atmospheric to an intermediate pressure, from which pressure fluid is taken and the pressure thereof raised by means of the pistons 15 to approximately double the intermediate pressure.

The form of the invention shown in Figs. 7 to 10, inclusive, comprises a 10 cylinder pump of the single stage variety, in which the volume of the pump may be varied through hydraulic pressure means. In this form of construction, there are five pistons 15a1, 15a2, 15a3, 15a4, and 15a5 which are received in cylinder bores in cylinder block 11a and five pistons 16a1, 16a2, 16a3, 16a4, and 16a5 which operate in bores on the other end of the cylinder block, the pistons of the first group being interspersed with those of the second group and each piston of each group being formed with valve portions which serve to valve the adjacent cylinder of the other group.

Power for operating the pump is applied through the shaft 12a which is coaxial with the stationary cylinder block 11a. The block includes a plurality of sets of cylinder bores 13a and 14a within which the pistons 15a and 16a are reciprocally mounted, respectively.

Annular housing 21a surrounds the cylinder block and is provided with a plurality of annular manifolds L1, H1, L2, and H2. L1 and L2 are low pressure manifolds and communicate with each other and with the suction line L3 as indicated schematically at the top of Fig. 7 and in

Fig. 10. H1 and H2 are high pressure manifolds and communicate with each other and with the high pressure or delivery manifold line H3. The manifold L1 communicates through an annular port 25a in the cylinder block with the valve chamber portions 25a' in cylinders 13a, cylinder heads 26a being provided in each cylinder 14a for closing off such cylinder from the port 25a and providing pressure chambers 27a therein.

The high pressure manifold H2 communicates through an annular port 25a' with the valve chambers 29a of cylinders 14a. This port is closed off from the other cylinders 13a by cylinder heads 32a which provide pressure chambers 33a in cylinders 13a.

High pressure manifold H1 communicates through a port 23a with the valve chamber portion in cylinders 13a only and low pressure manifold L2 communicates through ports 31a with the valve chamber portion of the cylinders 14a only.

The pistons are all formed with a reduced section which serve as passages for connecting the various ports at different times and are formed with connecting rod ends 17a and 18a terminating in ball ends 17b and 18b respectively.

A wobble disk 35a is arranged to reciprocate the pistons 15a while a second wobble disk 36a serves to reciprocate the other group of pistons 16a. Each wobble disk is supported on the pump

shaft 12a for rotation therewith, and is angularly adjustable relative to the axis of the shaft to vary the piston stroke. Each wobble disk comprises a hub 37a pivoted on the pump shaft by a pin 38a extending throughout the shaft and hub.

Said hub has attached thereto a wobble plate 39a which carries an outer ring 40a and an annular plate 41a. Bearing against the inner face of wobble disk 39a are a plurality of shoes 42a, the shape of which can best be seen in Fig. 8.

One side of each of said shoes is formed with a spherical pocket fitting the ball 17b or 18b on the pistons. The other side of said balls are contacted by a spherical surface formed on annular rings 43a which bear against and are slidable upon the plate 41a. The plates 39a and 41a are spaced by means of a ring 44a and are clamped in place by the nut 45a. A ring 46a may also be provided, said ring being rotatable relative to ring 44a and received in suitable cut-away portions on the shoes 42a and seat rings 43a. It will be noted that if the shaft 12a is rotated with the wobble plates in the position shown, the pistons will be reciprocated in their cylinder bores and that the extent of reciprocation depends upon the angular position of the wobble disk.

To reduce friction and wear a film of oil under pressure is preferably maintained between the balls and their seats and also between the shoes and the wobble plate 39a. This is preferably accomplished by forming the pistons with axial bores 50a communicating through an opening 51a in the shoe, which communicates with suitably formed grooves 52a and 53a in the flat surface of the shoe 42a (Fig. 8). The axial bore 50a

is intercepted by a transverse bore 54a which terminates in a groove 55a in the piston rod. Formed on the outer surface of the cylinder block is a groove 56a to which oil is delivered under pressure as through nipple 57a. It will be noted that when the piston is near the center of its stroke, a passage 58a will align with the groove 55a, thus allowing oil to flow through said various passages to the grooves 52 and 53a and also to the space between the balls and their seats. It will also be noted that the length of

time per revolution will vary with the piston stroke. When the pump is operated at a full stroke, the oil supply will be connected to the lubricating passages only a relatively small part of the time, whereas when the stroke is very small (when high pressures are developed) the lubricating oil is almost constantly in communication. Whereas in the form shown in Figs. 1 to 6, the adjustment of the wobble disks is effected by means of a sleeve surrounding the operating shaft, the present form accomplishes such adjustment by forming the shaft 12a hollow and providing within said shaft an axially slidable member to perform this function. This member comprises an adjusting slide 61a which has a slot 62a to receive the wobble disk journal pin 38a' and it is also provided with two pins 63a which carry shoes 64a which are slidable within slots 65a in the shaft 12a. Said pins also carry shoes 66a which operate in sloping slots 67a formed in the hub 50a' of the wobble disk. It will be seen, therefore, that axial movement of the adjusting slide 61a will cause the wobble disks to be moved about their journal pins 38a and 38a' due to the relative angles of the slots 65a and 67a. The slots are so arranged that when the adjusting slide 61a is moved fully to the left (Fig. 7) both wobble disks will stand at zero volume, viz: with the wobble plates 39a at right angles to the pump shaft 12a.

It would appear from Fig. 7 that journal pins 38a and 38a' are located 90° from each other. In an actual construction of such a 10 cylinder pump, the pins 38a and 38a' are displaced only 54° from each other. By this arrangement each of the pistons will be displaced 90° out of phase with the adjacent piston of the other set and, therefore, will be able to serve to valve the fluid moved by such adjacent piston.

While the adjacent slide 61a may be moved by hand or other means, it is often desirable to provide hydraulic means for such adjustment. This is accomplished in the present instance by forming the adjusting slide with an extension 61a' which is connected through a ball bearing 70a with the piston 71a fitted within a cylinder 72a. Connected to the left end of said cylinder is a port 73a and connected to the right part of said cylinder is a port 74a. These ports lead to a valve cylinder 75a within which is slidably mounted the piston valve member 76a preferably formed generally as shown. Ports 77a and 78a lead from a conduit 79a which is connected to a drain pipe leading to a sump. Oil under pressure is led to the valve cylinder through a conduit 80a. It will be seen that if the valve piston 76a is moved to the right, oil under pressure will be admitted from 80a through 74a to the rear of the piston 71a causing it to move to the left and therefore reducing the stroke of the pump. During this time the discharge port 73a is opened to port 77a. This adjusting motion continues until the piston valve 76a is restored to its central position. If it is now moved to the left the reverse operation will occur, the piston 71a will move to the right and the pump stroke will be increased. The operation of this form of pump will be clear from a study of Fig. 10. The directions of movements of the various pistons are indicated by the arrows appearing thereon; similarly curved arrows show the flow of the working fluid at the time indicated.

It will be noted that two pistons 16a1 and 16a5 of the one group are on their upward (intake) stroke. It will also be noted that, at this time, the fluid is so valved by the adjacent piston of the

other group of pistons that fluid is drawn from the intake manifold L1.

By referring to those pistons 16a3 and 16a4 which are on their downward stroke (delivery) it will be noted that the fluid displaced thereby is discharged into the delivery manifold H1. It will be noted also that pistons 15a2 and 15a3 which are on their downward (intake) stroke are so valved by their adjacent pistons that they draw fluid from the intake manifold L2 and that those pistons 15a4 and 15a5 which are on their upward (delivery) stroke are so valved that they discharge fluid into the delivery manifold H2.

As indicated in dotted lines in Figs. 7 and 10, the manifolds H1 and H2 are connected together and to a common delivery manifold H3; similarly the intake manifolds L1 and L2 are connected together to a common intake conduit L3. Thus all pistons draw fluid from a common intake and deliver to a common delivery conduit, thus providing a single stage pump.

It is to be noted that, if the manifolds H1 and H2 are not connected together, it will be possible to deliver two streams of fluid which will be equal in amount if the pistons are all of the same area, or in a different but definite proportion if the pistons of one group have a different area from those of the other group. It is also to be noted that if the inlet manifolds L1 and L2 are not connected together and the discharge manifolds H1 and H2 are not connected together, the pump may be used to pump two independent streams of fluid.

Furthermore, the device may be used as a flow divider by supplying liquid under pressure to one pair of manifolds and by having the other manifolds connected to independent circuits. In this event, no external power is applied to or taken from the drive shaft.

While the above description has referred to applicant's illustrative embodiments as a "pump" it is to be understood that it may also be used as an hydraulic motor by supplying to it fluid under pressure through either the manifolds H1 and H2 or L1 and L2.

It is intended that the patent shall cover, by suitable expression in the appended claims, whatever features of patentable novelty exist in the mechanism disclosed.

I claim:

1. An hydraulic unit of the positive displacement type comprising a shaft, a plurality of sets of cylinders, the cylinders of one set being interspersed with those of the other set, each cylinder having a pressure chamber and a valve space, pistons reciprocable in said cylinders, each piston being shaped to form a valve body movable in the associated valve space, supply manifold means, delivery manifold means, valve passages connecting said manifold means with the pressure chamber of each cylinder through the valve space of an adjacent cylinder, whereby the piston in one cylinder of a set controls the valving of said adjacent cylinder of another set, and means on said shaft for reciprocating the pistons in said adjacent cylinders substantially 90° out of phase.

2. An hydraulic unit comprising a shaft, a pair of cylinders, each having a pressure chamber and a valve space, pistons reciprocable in said cylinders, each forming a valve body movable in the associated valve space, supply manifold means, delivery manifold means, valve passages connecting said manifold means with the pressure chamber in each cylinder through the valve space in the other cylinder, whereby the piston in each

cylinder controls the valving of the other cylinder, and a separate wobble disk on said shaft for actuating each of said pistons.

3. An hydraulic unit comprising a shaft, a pair of cylinders, each having a pressure chamber and a valve space, pistons reciprocable in said cylinders, each forming a valve body movable in the associated valve space, supply manifold means, delivery manifold means, valve passages connecting said manifold means with the pressure chamber in each cylinder through the valve space in the other cylinder, whereby the piston in each cylinder controls the valving of the other cylinder, separate wobble disks on said shaft for actuating said pistons, and means for supporting said wobble disks on said shaft so as to reciprocate said pistons substantially 90° out of phase.

4. An hydraulic unit comprising a shaft, a pair of cylinders, each having a pressure chamber and a valve space, pistons reciprocable in said cylinders, each forming a valve body movable in the associated valve space, supply manifold means, delivery manifold means, valve passages connecting said manifold means with the pressure chamber in each cylinder through the valve space in the other cylinder, whereby the piston in each cylinder controls the valving of the other cylinder, separate wobble disks on said shaft for actuating said pistons, means for supporting said wobble disks on said shaft so as to reciprocate said pistons substantially 90° out of phase, and means for simultaneously adjusting the angles of said wobble plates for varying the strokes of said pistons.

5. An hydraulic unit of the positive displacement type comprising a shaft, separate groups of axially extending cylinders, pistons in one group of cylinders having operating means extending in one direction, pistons in another group of cylinders having operating means extending in the opposite direction reciprocable in said cylinders, a single delivery manifold common to all cylinders, an inlet manifold communicating with the cylinders associated with one group of pistons, a second inlet manifold communicating with said other cylinders, separate wobble disks on said shaft for reciprocating each group of pistons, and means for simultaneously adjusting the angle of said wobble disks for varying the strokes of said pistons.

6. An hydraulic unit comprising a shaft, a cylinder block having a plurality of axial cylinders, pistons reciprocable in said cylinders, alternate groups of pistons having operating means extending in opposite directions, means on said shaft for reciprocating the pistons having their operating means extending in one direction, separate means on said shaft for reciprocating the pistons having their operating means extending in the opposite direction, and mechanism for simultaneously adjusting said piston reciprocating means, to vary the strokes of said pistons of each group simultaneously.

7. An hydraulic unit comprising a shaft, a cylinder block having a plurality of axial cylinders, pistons reciprocable in said cylinders, alternate groups of pistons having operating means extending in opposite directions, means on said shaft for reciprocating the pistons having their operating means extending in one direction, separate means on said shaft for reciprocating the pistons having their operating means extending in the opposite direction, and mechanism movable longitudinally of said shaft for simultaneously adjusting said piston reciprocating means,

to vary the strokes of said pistons simultaneously.

8. An hydraulic unit comprising a relatively rotatable shaft and cylinder block, cylinders in said block, pistons reciprocable in said cylinders, a wobble disk for reciprocating said pistons, and means for connecting said disk to said piston rod including a slidably mounted crosshead in alignment with said rod, means loosely connecting said rod to said crosshead, and means for connecting said disk to said crosshead for reciprocation thereby.

9. An hydraulic unit comprising a relatively rotatable shaft and cylinder block, a piston and piston rod reciprocable in said block, means on said shaft for reciprocating said piston including a wobble disk, means for transmitting reciprocating forces from said disk to said piston substantially without imposing side thrust on said piston, including a slidably mounted crosshead loosely connected to said piston rod, thrust members in said crosshead on opposite sides of said disk, means connecting one thrust member to said sleeve, said other thrust member being adapted to engage the end of said piston rod.

10. An hydraulic unit comprising a relatively rotatable shaft and cylinder block, a piston and piston rod reciprocable in said block, means on said shaft for reciprocating said piston including a wobble disk, means for transmitting reciprocating forces from said disk to said piston substantially without imposing side thrust on said piston, including a slidably mounted crosshead loosely connected to said piston rod, thrust members in said crosshead on opposite sides of said disk, hemispherical wear members movably mounted in said thrust member for engagement by said disk, and means yieldingly connecting one thrust member to said crosshead, said other thrust member being adapted to engage the end of said piston rod.

11. An hydraulic unit comprising a relatively rotatable shaft and cylinder block, a piston and piston rod reciprocable in said block, means on said shaft for reciprocating said piston including a wobble disk, means for transmitting reciprocating forces from said disk to said piston substantially without imposing side thrust thereon, including a crosshead formed by a slidably mounted sleeve loosely connected to said piston rod, thrust members mounted in said sleeve engaging opposite sides of said disk, and means yieldingly connecting one thrust member to said sleeve, said other thrust member being adapted to engage the end of said piston rod.

12. The combination in an hydraulic unit having cylinders and pistons, of a shaft, a wobble disk for reciprocating said pistons including a hub surrounding said shaft and pivoted thereon for angular adjustment relatively thereto, means for adjusting the angular position of said hub including a grooved sleeve slidably supported on said shaft and extending through said hub, a pin mounted in the groove of said sleeve and connected to said hub whereby movement of said sleeve longitudinally of said shaft varies the angular adjustment of said wobble disk.

13. An hydraulic unit comprising a pair of cylinders, each having a pressure chamber and a valve space, pistons reciprocable in said cylinders, each piston forming a valve body movable in the associated valve space, a supply manifold, a delivery manifold, valve passages connecting at times said supply manifold with the pressure chamber in one of said cylinders, and, at other

11

times, connecting the said pressure chamber with the delivery manifold, through the valve space in the other cylinder, whereby the piston in each cylinder controls the valving of the other cylinder, operating means for actuating said pistons in such a manner as to reciprocate said pistons substantially 90° out of phase.

14. An hydraulic unit comprising a plurality of pairs of cylinders, each having a pressure chamber and a valve space, pistons reciprocable in said cylinders, each piston forming a valve body movable in the associated valve space, a supply manifold, a delivery manifold, valve passages connecting at times said supply manifold with the pressure chamber in one of said cylinders of a pair, and, at other times, connecting the said pressure chamber with the delivery manifold, through the valve space in the other cylinder of said pair whereby the piston in each cylinder of a pair controls the valving of the other cylinder of said pair, operating means for actuating said pistons in such a manner as to reciprocate the pistons of a pair substantially 90° out of phase.

15. An hydraulic unit comprising a pair of cylinders, each having a pressure chamber and a valve space, pistons reciprocable in said cylinders, each piston forming a valve body movable in the associated valve space, a supply manifold and a delivery manifold for each cylinder of said pair, valve passages connecting at times said supply manifold of one of said pair of cylinders with the pressure chamber in one of said cylinders, and, at other times, connecting the said pressure chamber with the respective delivery manifold through the valve space in the other cylinder, whereby the piston in each cylinder controls the valving of the other cylinder, operating means for actuating said pistons in such a manner as to reciprocate said pistons substantially 90° out of phase.

16. An hydraulic unit comprising a power shaft, a cylinder, a piston reciprocable in said cylinder, operating connections between said shaft and said piston including a wobble plate and a shoe slidable on said plate and operatively connected to said piston, and means for delivering lubricant between said relatively slidable shoe and plate comprising a source of pressure for said lubricant, a duct leading therefrom to said cylinder at a point always covered by said piston, a lubricant passage in said piston connecting at one end to the space between said relatively slidable shoe and wobble plate and connecting at the other end to a transverse port in said piston so located that when the piston is in substantially mid-position it aligns with said duct which connects to the pressure source, the said duct and port being so dimensioned that communication between them is interrupted except when the piston is near mid-stroke.

17. An hydraulic unit comprising a power shaft, a cylinder, a piston reciprocable in said cylinder, operating connections between said shaft and said piston including a wobble plate, a

12

shoe slidable on said plate, said shoe being formed with a spherical seat in which a ball on said piston seats, and means for delivering lubricant to the space between the plate and the shoe and between the ball and its seat comprising a source of pressure for said lubricant, a duct leading therefrom to said cylinder at a point always covered by said piston, a lubricant passage in said piston connecting at one end to the relatively slidable surfaces between the shoe and the plate and between the shoe and the ball and connecting at the other end to a transverse port in said piston so located that when the piston is in substantially mid-position it aligns with said duct which connects to the pressure source, the said duct and port being so dimensioned that communication between them is interrupted except when the piston is near mid-stroke.

18. An hydraulic unit comprising a power shaft, a cylinder, a piston reciprocable in said cylinder, operating connections between said shaft and said piston including relatively slidable members and means for delivering lubricant to said relatively slidable members comprising a source of pressure for said lubricant, a duct leading therefrom to said cylinder at a point always covered by said piston, a lubricant passage in said piston connecting at one end to said relatively slidable surfaces and connecting at the other end to a transverse port in said piston so located that when the piston is in substantially mid-position it aligns with said duct which connects to the pressure source, the said duct and port being so dimensioned that communication between them is interrupted except when the piston is near mid-stroke.

19. An hydraulic unit comprising a power shaft, a cylinder, a piston reciprocable in said cylinder, operating connections between said shaft and said piston including relatively slidable members and means for delivering lubricant to said relatively slidable members comprising a source of pressure for said lubricant, a duct leading therefrom to said cylinder at a point always covered by said piston, a lubricant passage in said piston connecting at one end to said relatively slidable surfaces and connecting at the other end to a transverse port in said piston so located that when the piston is in substantially mid-position it aligns with said duct which connects to the pressure source.
